(57) **CLAIM**

The ornamental design for a multi-purpose container, as shown, and described.

DESCRIPTION

FIG. 1 is a perspective view of a new, original and ornamental design for a multi-purpose container, showing our new design;

FIG. 2 is a right side elevation view thereof;

FIG. 3 is a rear elevation view thereof;

FIG. 4 is a left side elevation view thereof;

FIG. 5 is a front elevation view thereof;

FIG. 6 is a top plan view thereof;

FIG. 7 is a bottom plan view thereof; and,

FIG. 8 is an exploded view thereof.

The broken lines in the drawings depict portions of the multi-purpose container that form no part of the claimed design.
